UNITED STATES PATENT OFFICE

GEORGE W. BOWERS, OF SOMERVILLE, MASSACHUSETTS, ASSIGNOR, BY MESNE ASSIGNMENTS, TO HAMMEL, RIGLANDER & CO., OF NEW YORK, N. Y., A CORPORATION OF NEW YORK.

PEG-WOOD SHARPENER.

933,414.

Specification of Letters Patent. Patented Sept. 7, 1909.

Application filed January 22, 1909. Serial No. 473,729.

To all whom it may concern:

Be it known that I, GEORGE W. BOWERS, of Somerville, in the county of Middlesex and State of Massachusetts, have invented 5 certain new and useful Improvements in Peg-Wood Sharpeners, of which the following is a specification.

Watch and clock makers and repairers employ in the course of their work a cylindrical rod or stick of a special wood, known 10 as peg wood, the stick being reduced at one end to a fine point which is adapted to enter small orifices, such as bearings in watch and clock parts to remove dust, oil, etc., therefrom.

The pointed end of a peg-wood stick requires a very slender or attenuated terminal portion adapted to act on all parts of a small hole or bearing, this end portion being best 20 formed by imparting a longitudinally concave form to the cone formed by sharpening the stick.

Owing to the flexibility of the peg-wood, it has been found difficult to rapidly and 25 effectively form a pointed portion having a concave taper by ordinary appliances, such as are used in sharpening pencils, etc.

My invention has for its object to provide an effective sharpening device adapted 30 to form a pointed end portion on a peg-wood stick, such pointed portion having a concave taper, and having therefore an attenuated terminal of desirable length.

The invention consists in the improvements which I will now proceed to describe 35 and claim.

Of the accompanying drawings, forming a part of this specification,—Figures 1 and 2 represent elevations showing different sides 40 of a peg-wood sharpener embodying my invention. Fig. 3 represents a fragmentary sectional view showing the cutter and the rest, hereinafter referred to, and a peg-wood stick in the position it occupies at the commencement of the sharpening operation. Fig. 4 represents a view similar to Fig. 3, showing the peg-wood stick at the completion 45 of the sharpening operation. Fig. 5 represents a side view of the acting end portion of a sharpened peg-wood stick. Figs. 6 and 7 represent elevations of an attachment for watchmakers' lathes, said attachment embodying the essential features of the invention.

The same reference characters indicate the 55 same parts in all the figures.

In the drawings, 12 represents a shaft journaled in bearings in a suitable supporting frame, and adapted to be rotated by any suitable means, such as a crank 13, as shown 60 in Figs. 1 and 2. To the shaft 12 is affixed a substantially circular cutter 14 which is preferably formed by cutting tangential slots 15 in the periphery of a metal disk of suitable thickness, the outer side of each slot 65 intersecting the periphery of the disk, and forming a knife having a shaving cutting edge 16, the said knife being slightly bent outwardly to raise the cutting edge above the periphery of the disk, thus giving each 70 knife the requisite shaving cut and clearance.

17 represents a holder for the peg-wood stick 18 to be sharpened, said stick being of cylindrical form, a special wood being employed having qualities which adapt it for 75 the cleaning of small holes, bearings, etc. The holder 17 is tubular, and has a frictional fit on the stick, the latter being movable endwise in the holder, and rotatable on its own axis. The stick may be fed forward by hand 80 or by automatic means to present it to the cutter, and may be rotated either by hand or by the automatic rotation of the holder 17, said automatic rotation being effected by the means hereinafter described.

The relative arrangement of the cutter and the holder 17 is such that the axis of the stick is on a tangent with the periphery of the cutter, so that each of the cutting knives, moving in a circular path by the rotation of 90 the cutter, is adapted to perform its part in forming a tapered end portion 18' (Fig. 5), the surface of which is longitudinally concave, and has an attenuated terminal portion 18², the taper of which is considerably less 95 than that of the main body of the tapered end portion.

19 represents a fixed rest which in Figs. 1 and 2 is shown as secured by a screw 20 to an arm 21 forming a part of the supporting 100 frame. The rest 19 has a segmental end face 22 which has the same curvature as the path in which the cutting knives move, and is opposed to the cutter so that it bears on one side of the tapered end portion 18' during 105 the operation of forming the latter, as indicated in Figs. 3 and 4.

The segmental end face 22 and the per-

imeter of the cutter collectively form a tapered throat between which the end portion 18' of the stick is formed, the face 22 supporting the said end portion along a line opposite the cutter, and in such manner as to prevent outward deflection of the stick by the pressure of the cutter against it, the apex or narrow end of said throat coinciding with the axis of the stick, and the length of the 10 segmental face 22 being such that it is adapted to support all parts of the tapered end portion against the pressure of the cutter, as indicated in Fig. 4.

At the commencement of the operation of 15 sharpening a fresh stick which has not before been sharpened, the blunt end of the stick bears on the upper portion of the segmental face 22, as shown in Fig. 3, the stick being supported continuously by the segmental face 22 from the beginning to the end 20 of the sharpening operation, as will be evident from an inspection of Figs. 3 and 4.

I regard it as important that the segmental face 22 be arranged to bear on the 25 entire length of the tapered portion of the stick, including the attenuated terminal 18', this portion being particularly liable, on account of its flexibility, to yield to the pressure of the cutter against it. The slightest 30 yielding of the terminal portion while it is being rotated in contact with the cutter, would prevent the proper formation of said terminal portion.

The rest 19 may be adjustably secured to 35 the frame by means of a slot 23 in the arm 21, said slot receiving and permitting the adjustment of the attaching screw 20, and of the rest 19.

The holder 17, as shown in Fig. 1, is adapted 40 to rotate in a bearing formed for its reception in an arm 24, forming a part of the supporting frame, and is provided with a worm gear 25 which receives a slow rotary motion from the cutter shaft 12 through a 45 spur gear 26 affixed to said shaft, an intermediate shaft 27 journaled in the supporting frame, a small spur gear or pinion 28 affixed to the shaft 27, and meshing with the gear 26, and a worm 29 affixed to the shaft 27 and 50 meshing with the worm gear 25.

The device as illustrated in Figs. 1 and 2, is adapted for hand operation. The cutter may, however, be rotated by power.

In Figs. 6 and 7 I show my invention embodied in an attachment adapted to be applied to a watchmaker's lathe, the bed 30 of which is shown in Fig. 6. Said attachment includes a frame composed of two elongated side portions 31, 31, united at their lower 55 ends by one or more rivets 32, and separated at their upper ends by a block 33 located between the separated upper ends of the side pieces and attached thereto by a screw 34, and an arm 35 affixed to the block 33 and 60 having an ear 36 on which is formed a tu-

bular holder 37 for the stick 18. The shaft 12 carrying the cutter 14 is journaled in bearings in the separated upper ends of the side pieces 31. The block 33 serves not only as a support for the arm 35 and the stick 70 holder 37, but also as a substitute for the rest 19, said block having a segmental face 38 which corresponds in arrangement and function with the segmental face 22 above described. 75

The shaft 12 may be, in this embodiment of my invention, rotated by power applied to it from the lathe, the peg-wood stick being fed and rotated by hand.

I claim:

1. A peg-wood sharpener comprising a holder in which a peg-wood stick is rotatable and longitudinally movable, a rotary cutter having one or more shaving knives which move in a circular path, so related to the holder as to form a longitudinally concave pointed portion on a stick which is axially rotated and moved endwise relatively to the cutter, and a rest having a curved face opposed to the perimeter of the cutter, said rest and cutter collectively forming convex sides of a tapering throat, the apex of which coincides with the axis of the stick, the rest holding the said tapered portion against the cutter and preventing the deflection of said portion from the axis of the stick. 90

2. A peg-wood sharpener comprising a rotary holder in which a stick is longitudinally movable, a rotary cutter having one or more shaving knives which move in a circular path, a rest having a curved face opposed to the perimeter of the cutter, and adapted to conform to the curvature imparted by the cutter to the stick and hold the end of the stick against the cutter during the sharpening operation; and mechanism for transmitting rotary motion from the cutter to the stock holder. 100

3. A peg-wood sharpener comprising a rotary holder in which a peg-wood stick is longitudinally movable, a rotary cutter having one or more shaving knives which move in a circular path, a rest having a curved face opposed to the perimeter of the cutter, and adapted to conform to the curvature imparted by the cutter to the stick and hold the end of the stick against the cutter during the sharpening operation, a spur gear affixed to the cutter, a worm gear affixed to the stick holder and an intermediate shaft having a gear meshing with the spur gear, and a worm meshing with the worm gear. 110

In testimony whereof I have affixed my signature, in presence of two witnesses.

GEORGE W. BOWERS.
